UNITED STATES PATENT OFFICE

124,375

DESIGN FOR A PILLOWCASE OR SIMILAR ARTICLE

Elie Sutton, Brooklyn, N. Y.

Application August 22, 1940, Serial No. 94,558

Term of patent 3½ years

To all whom it may concern:

Be it known that I, Elie Sutton, a citizen of Syria, Republic of France, residing at Brooklyn, county of Kings, and State of New York, have invented a new, original, and ornamental Design for a Pillowcase or Similar Article, of which the following is a specification, reference being had to the accompanying drawings, forming part thereof, wherein—

The letters M and R are merely illustrative of the style and arrangement of initials included in the design.

I claim:

The ornamental design for a pillowcase or similar article, substantially as shown and described.

ELIE SUTTON.
